UNITED STATES PATENT OFFICE.

THOMAS S. WARNER, OF SPRINGFIELD, OHIO.

CULTIVATOR.

1,108,286.

Specification of Letters Patent. Patented Aug. 25, 1914.

Application filed October 31, 1908. Serial No. 460,417.

To all whom it may concern:

Be it known that I, THOMAS S. WARNER, a citizen of the United States of America, and resident of Springfield, Ohio, have invented 5 a certain new and useful Improvement in Cultivators, of which the following is a specification.

My invention relates to what are commonly known as lister cultivators—that is to 10 say, machines adapted to cultivating corn that has been planted in trenches by means of a lister. The prior art is exemplified, to some extent at least, in Patent No. 701,972.

My present invention contemplates certain 15 improvements on the lister cultivator of the general type disclosed in said patent. For example, by my improved lister cultivator, as herein described and illustrated, I provide means for mounting and varying the 20 distance between the shovels. Furthermore I provide a construction by which these shovels are interchangeable for the purpose of varying the distance between them. In addition I provide improved means for 25 mounting and varying the distance between the cultivator disks, as well as for mounting and varying the distance between the 30 cultivator wheels. In fact, with my improved construction as herein disclosed, it is possible not only to vary the distance between the cultivator disks, but also to change them from the in-throw to the out-throw with or without interchanging them and with or without disengaging them from 35 their mountings or bearings. This I find to be of considerable advantage, as it simplifies and facilitates the operation of changing the disks from the in-throw to the out-throw, or from the out-throw to the in-throw, according 40 to the requirements of the work for which a cultivator of this particular character is designed. Again I provide improved means for varying the angularity and slant of the cultivator disks, whereby 45 such adjustment can be accomplished readily and according to the character of the work. Also, by my improved construction, I provide means for raising and lowering the cultivator disks independently of the shovels, 50 as well as means for raising and lowering the shovels independently of the disks. As will hereafter more fully appear, however, and by reason of a toggle-like connection between the wheels and frame of the cultivator, the raising of the cultivator disks tends 55 also to give the entire cultivator, except the

wheels of course, a slight bodily lift or upward motion and at the same time to vary the balance, thus relieving the neck weight of the pole.

As still another feature of improvement, I provide a couple of hand levers having an interlocking connection between them, whereby the raising and lowering of the shovels can be made to accompany the raising and lowering of the disks by simply grasping and operating the lever which is allotted to the said disks. With this arrangement, I find that the control of the cultivator in the field is greatly facilitated 60 and improved.

Still another feature of improvement consists in the provision of a so-called hard oiler for the cultivator disks, which disks are arranged for instantaneous adjustment 65 from the in-throw and out-throw, and vice versa, as previously explained.

To the foregoing, and other useful ends, my invention consists in matters hereinafter set forth and claimed and illustrated in the 70 accompanying drawings, in which—

Figure 1 is a side elevation of a lister cultivator embodying the principles of my invention, the cultivator disks and shovels being shown resting on the ground. Fig. 2 is 75 a similar view showing the disks and shovels raised from the ground. Fig. 3 is a plan of the said lister cultivator, it being observed that the disks and shovels are set for the in-throw. Fig. 4 is a rear view of the 80 said lister cultivator, showing the plank or connecting beam which is employed for connecting such cultivator with another similar cultivator, it being understood that these cultivators are usually employed in pairs, 85 one being left-handed and the other right-handed, and that the driver occupies the seat which is supported on the said plank or connecting beam on the point midway between the two cultivators, thus bringing the 90 driver into a position to manipulate the hand-levers of both cultivators. Fig. 5 is an enlarged detail view of one of the mountings for the wheel and disk on one side of the cultivator. Fig. 6 is an enlarged detail 95 view illustrating the construction for changing the horizontal angularity or slant of one of the disks. Fig. 7 is an enlarged sectional view of one of the disks showing the improved hard oiler for the same. Fig. 8 is an 100 enlarged cross section on the line 8—8 of Fig. 7. Fig. 9 is an enlarged section lon-

itudinally of the squared shaft upon which the shovels are mounted, and which carries the arms or lifting connections by which the disks are raised and lowered. Fig. 10 is a detail perspective view of the portion of the said square shaft showing means by which the arm is operated to raise and lower the shovel, and showing a portion of the arm which is loose on said shaft and by which the disks are raised and lowered. Fig. 11 is a detail view showing the squared shaft in cross section, and showing the bearing in which the same is adapted to turn or rock. Fig. 12 is a detail view showing the bottom of one of the clamps or mountings by which the shovel beams are secured to the said squared shaft which latter is in the nature of a rock shaft. Fig. 13 is a view similar to Fig. 3, but showing the disks and shovels reversed or adjusted in a position for the out-throw—that is to say, the adjustment by which the disks throw the dirt outwardly rather than inwardly.

As thus illustrated, my invention comprises a tongue A, to which are rigidly secured the side members or frame bars B. A transverse axle C is mounted in suitable bearings on said tongue and side bars, and a squared rock shaft D is mounted in the bearings secured to the ends of said bars B. The disk-like wheels E are mounted upon the lower ends of the spindles or arms e, and the latter have their upper ends hung in swinging castings or arms e¹, which latter are in turn hung on the said axle C. The said castings are provided with bifurcated upper end portions between which are arranged the bearings e² by which the said axle is supported on the frame. With this arrangement the castings or swinging arms e¹ can be moved toward and away from each other on the said axle. In order to hold the said castings or arms in different positions on the said axle the upper ends of the same are provided with openings e³ adapted to receive the collars e⁴ which are secured on the axle with set screws e⁵. In this way the said castings or arms e¹ are held against movement toward and away from each other, and at the same time left free to swing upon the said axle. Brace rods e⁶ connect the lower ends of the wheel spindles e with the tongue A, so as to hold the wheels in position to support the tongue and frame and other parts in a suitably elevated position. It will be seen that the spindles e and the castings or arms e¹ are pivotally connected in such manner that each wheel spindle and its allotted casting form a toggle joint connection between the cultivator frame or body and the supporting wheel E.

The angularly disposed cultivator disks F are mounted upon spindles which are rotatably carried or inserted in the lower end

portions f of the castings e¹. It will be seen that each spindle consists of a lower end section f¹ and an upper section f², the two sections being pivotally connected together by a bolt f³ and a collar f⁴, which latter is clamped on the spindle section f¹. Another collar f⁵ is clamped on the section f², and this collar is connected with the spindle section f¹ by means of a rod f⁶. In this way the angular relation of the two sections can be changed or varied as shown in Fig. 6, by sliding the collar f⁵ back and forth on the spindle section f². This, of course, will change the horizontal angularity of the cultivator disks, so that they may work according to different requirements. In order that each disk may be oiled by hard oil or grease, these spindle sections f¹ are preferably provided with a longitudinal groove f⁷, and the end is threaded to receive a threaded grease cap f⁸. The sleeve f⁹ of the disk extends for some distance over the said spindle and is held against endwise displacement by the collar f¹⁰ and the said cap f⁸. The hub f¹¹ of the disk is provided with a threaded portion f¹², and with an interior or unthreaded cavity f¹³. Thus when the cap f⁸ is screwed in place it first forces the hard oil or grease through the duct or groove f⁷, and then disengages from the threaded portion of the hub f¹¹, as shown in Fig. 7. This leaves the disk in position to turn freely, and the caps f⁸ of the two disks are held against turning by the supports or brace rods f¹⁴. The arms f¹⁵ are loosely mounted on the rock shaft D and connected together by a bar f¹⁶ to which the upper ends of the rods f¹⁴ are suitably secured. An arch or arm f¹⁷ connects the bar f¹⁶ with the rock shaft D, being loosely mounted on the latter. The shovels G are secured to beams g, which latter are rigidly secured near the outer ends of the rock shaft D, in such a way as to allow a lateral adjustment, by means of which the distance between the shovels can be varied. Preferably, the said shovel beams g are secured to the rock shaft by means of clips g¹, which latter have cross grooves g², adapted to be engaged by the end portions of said shovel beams, in such a way that a forward or backward adjustment of the beam will give a lateral adjustment to the shovel. In Fig. 3 it will be seen that these shovel beams converge toward the rock shaft, while in Fig. 13 the said shovel beams converge rearwardly. These shovel beams are interchangeable, and it is the crossed grooves g² which accommodate the said beams in their different positions on the bottom of said clips. In this way the shovels can be made to trail behind the cultivator disks in the usual manner, and for the well known purposes, regardless of the distance between the said disks. In Fig. 3 the disks and shovels are set for the in-throw while in Fig. 13 the same are set for 130

the out-throw. In Fig. 13 the rods f^{14} are shifted into engagement with the bracket f^{18} located centrally of the bar f^{16} . In this way the disks are supported in either position and the change is made by simply swinging the disks over from one position to the other, the spindle of each disk being rotatably mounted in one of the castings e^1 . Any suitable means can be employed for holding the spindles of the disks against endwise displacement in the bearings f . The wheel spindles e are held against displacement from the said castings by means of collars e^6 secured to said spindles and held in place by set screws e^7 , said castings being each provided with a cavity or opening e^8 to accommodate said collar, as shown in Fig. 5. The brace rods H have their forward ends pivotally connected with the castings e^1 and their rear ends pivotally connected with the brackets h carried by the arms f^{15} . In this way the raising and lowering of the arms f^{15} not only tends to raise the cultivator disks f , but also tends to manipulate the toggle connections between the wheels E and the frame of the cultivator, thus slightly raising the said frame on the said wheels when the disks are raised from the ground and shifting the wheels under the cultivator, thereby changing the balance.

In order to rock the rock shaft D and thereby raise and lower the shovels G , the said shaft is provided with an arm I , which latter is connected by a rod i with a hand lever i^1 . On this rod there is a loose sleeve i^2 which is secured to the said arm I and which is prevented from sliding off the end of the rod by the pin i^3 . A collar i^4 is secured to the said rod, and a spring i^5 is interposed between this collar and the sleeve i^2 . In this way the shovels are yieldingly held in the ground, and are free to yield to obstructions and rise against the pressure of said spring. The said hand lever i^1 is provided with a suitable hand operated latch or locking device adapted to engage a rack or segment J which is secured to a second hand lever j . This second hand lever is in turn provided with an ordinary hand operated latch or locking device adapted to engage a stationary rack or segment j^1 , which latter is mounted on the tongue of the cultivator. It will be understood that both hand levers are suitably pivoted at their lower ends so that they may be swung forward and back by the driver or operator who occupies the seat K . A rod j^2 connects the lever j with the arm or arch f^{17} , so as to raise and lower the shovels G and disks F when the two hand levers are locked together. It will be seen, however, that the hand lever i^1 can be operated independently of the other lever for the purpose of raising and lowering the shovels independently of the disks. On the other hand if necessary, the hand lever i^1 can

be held stationary while the other lever is manipulated to change the positions of the disks, without raising or lowering the shovels. By the interlocking arrangement between the two hand levers the lever j is, however, as explained, adapted to control the disks and shovels together, to raise and lower them in unison. The spring L connects the tongue with the rack J , thus serving to assist in raising the disks and shovels from the ground. By referring to Fig. 4 it will be seen that the two hand levers are inclined to the right, so as to be within reach of the driver occupying the seat K . This seat, it will be seen, is mounted on the cross plank or beam k which extends from one cultivator to the other, it being common practice to employ these cultivators in pairs. The cultivator shown, is a left-hand machine, and the plank or beam k would extend over to the right hand cultivator, the hand levers of which latter would incline to the left and thus be within reach of the driver. It is a matter of common knowledge that in using a cultivator of this particular type it is desirable at one time to have the disks set for an in-throw of the soil, while at other times and for another part of the general work of this particular kind of cultivating it is desirable to have the said disks set for an out-throw of the soil. As previously explained, my improved cultivator disks are adjustable from the in-throw to the out-throw, simply by swinging each disk over from one position to the other. The shovels which trail behind the disks are always, of course, adjusted according to the distance between the disks, and this is done by interchanging the shovel beams, as previously explained. It is evident that the said shovel beams can be interchanged, and thus shifted from one clip to the other. On the other hand, the clips themselves can be loosened in order to take off the shovel beams and the beams with their clips still attached can then be interchanged so that the clips are transferred from one end to the other of the rock shaft D upon which they are mounted. Thus considerable latitude of adjustment is given for all purposes, and in each case the adjustment or change is effected quickly and by exceedingly simple and effective means. At the same time the construction of the cultivator is both strong and light, and the parts are well balanced with respect to the different strains to which the cultivator is subject while in use.

With further respect to the changing of the disks from the in-throw to the out-throw, and vice versa, it will be seen that such adjustment can be accomplished by interchanging the disks and their jointed spindles—that is to say, by transferring one entire spindle and its disk from one casting e^1 to the other casting e^1 . For certain require-

ments and in some situations, this may be found desirable, although for ordinary purposes the disks are changed from one position to the other by simply swinging them over, and without removing their spindles from the said castings. In any event, however, the disk spindles are preferably supported by hanger rods or braces f^{14} , as explained, and these braces or hanger rods may be applied in various ways without departing from the spirit of my invention. Furthermore, each disk spindle is preferably jointed to provide it with an elbow portion, and the two sections of each spindle are preferably held or locked against relative movement by a link or brace rod f^6 , means being provided for varying the angular relation between the two sections of the spindles to vary the horizontal angularity of the disks.

20 Preferably, as explained, the cultivator disks F are changeable or adjustable from the in-throw and out-throw, and vice versa, without removing them from their spindles. This can be done, as stated, by either interchanging the spindles, or by rotating the same in their bearings on the lower ends of the castings c^1 , according to requirements. The construction can of course, be changed or modified more or less in order to accomplish these and other similar methods of adjustment without departing from the spirit of my invention. As shown, the hangers or brace rods f^{14} are secured at their lower ends to the caps f^8 by means of threads, in such a way that the braces can be made shorter or longer thus changing the vertical angle or slant of the disks, and thus prevent the latter from turning and hold the disks rigidly to their work. With this arrangement the said hangers or brace rods are in the rear of the disks, but it is obvious that they may be otherwise located, relative to the disks. For this reason I do not limit myself to the exact construction of arrangement shown and described. At their upper ends the hangers or brace rods f^{14} are secured to the cross bar f^{16} , in one of several positions, by means of a series of holes, thus securing additional adjustment for depth of disks.

50 What I claim as my invention is:

1. In a lister cultivator, a pair of angularly disposed cultivator disks, spindles on which said disks are mounted, bearings in which said spindles are mounted, said bearings permitting said spindles to be rotated to change the disks from the in-throw to the out-throw, a pair of shovels connected to trail behind said disks, said shovels mounted on a suitable rock shaft and brace rods extending from said rock shaft to a point adjacent said spindle bearings, and a pair of supporting wheels disposed in front of said disks.

65 2. In a lister cultivator, a pair of angularly disposed cultivator disks, spindles on which said disks are mounted, bearings in which said spindles are mounted, said bearings permitting said spindles to be rotated to change the disks from the in-throw to the out-throw, a pair of shovels connected to trail behind said disks, said shovels mounted on a suitable rock shaft and brace rods extending from said rock shaft to a point adjacent said spindle bearings, and a pair of supporting wheels disposed in front of said disks.

70 3. In a lister cultivator, a frame, a rock shaft carried thereby, shovel beams secured to said rock shaft, swingingly mounted cultivator disks, arms loosely mounted on said rock shaft, rods connecting said arms with said disks, a lever connected for rocking said shaft to raise and lower the shovels, a lever connected with said arms for raising and lowering the disks, and an interlocking connection between said levers, whereby one of said levers is operated to raise and lower both the disks and shovels.

75 4. In a lister cultivator, a frame, a rock shaft supported thereon, shovel beams rigidly secured to said rock shaft, swingingly mounted cultivator disks, arms loosely mounted on said rock shaft and connected with said disks, means for rocking said arms on the shaft to raise and lower the disks, and means for rocking said shaft to raise and lower the shovels.

80 5. In a lister cultivator, a rock shaft, a pair of clips secured to said rock shaft, each clip provided on its underside with a pair of crossed grooves, and a pair of interchangeable shovels provided with beams adapted to be secured to said grooves by the clips, said shovels being interchangeable from one clip to the other, and said clips being interchangeable from one end of the shaft to the other.

85 6. In a lister cultivator, a frame, an axle carried thereby, a pair of bearings hung on said axle, means for varying the distance between said bearings, a pair of wheel spindles hung on the lower ends of said bearings, wheels on said spindles, a pair of disk spindles mounted on the lower ends of said bearings, a pair of angularly disposed cultivator disks mounted on the rear ends of said disk spindles, means for bracing the wheel spindles and bearings, and means for bracing the disk spindles.

90 7. In a lister cultivator, a pair of angularly disposed cultivator disks, a pair of spindles on which said disks are mounted, each spindle comprising hinge connected sections, each spindle provided with an adjustable brace connecting the two sections thereof, adapted for varying the angular relation between the same, whereby the angularity or slant of the disks may be changed at will.

120

125

130

8. In a lister cultivator, the combination of a frame, a tongue supported in said frame, a pair of supporting wheels, toggle-like connections between the wheels and the frame, a rock shaft mounted in the rear of said frame, a rearwardly extending brace rod extending from said toggle connection to said rock shaft, and means for operating said rock shaft to raise and lower the frame

10 relatively to the said wheels.

9. In a lister cultivator, the combination of a frame, a tongue supported in said frame, a pair of supporting wheels, toggle-like connections between the wheels and the frame, a brace rod extending forwardly from said wheels to said tongue, a rearwardly extending brace rod connected to said toggle, and means to operate said toggle-like connections to raise and lower the

20 frame relative to the wheels.

10. In a lister cultivator, a frame, an axle mounted in said frame, a pair of down-

wardly extending toggle-like connections mounted on said axle, a pair of supporting wheels mounted in the lower ends of said connections, spindles connected to the mid point of said toggles, and cultivator disks mounted on said spindles.

11. In a lister cultivator, a frame, an axle mounted in said frame, a toggle-like connection mounted on said axle, and a supporting wheel mounted on the lower end of said toggle, a rock shaft supported in said frame to the rear of said axle, shovels mounted on said rock shaft and connections from said rock shaft to said toggle-like connection.

Signed by me at Springfield, Ohio, this 12 day of October, 1908.

THOMAS S. WARNER.
